GOVERNING MECHANISM

Filed July 26, 1929

UNITED STATES PATENT OFFICE

HENRY F. SCHMIDT, OF LANSDOWNE, PENNSYLVANIA, ASSIGNOR TO WESTINGHOUSE ELECTRIC & MANUFACTURING COMPANY, A CORPORATION OF PENNSYLVANIA

GOVERNING MECHANISM

Application filed July 26, 1929. Serial No. 381,374.

My invention relates to a fluid pressure governing mechanism, and it has for an object to provide a mechanism of the character set forth having improved operation.

According to one form of fluid pressure governing mechanism, described and claimed in the patent of A. T. Kasley, No. 1,732,812, filed October 22, 1929, fluid pressure varying as a function of the prime mover to be governed is provided by a centrifugal pump driven by the prime mover. This fluid pressure is imposed on a pressure-responsive element, on which is also imposed, in opposition to said pressure, a fluid pressure provided in an enclosed space by admitting a restricted flow of fluid under pressure and controlling the escape of fluid from the space by a pressure-relief valve. The setting of the governing mechanism is changed by varying the setting of the pressure-relief valve, which therefore constitutes the speed changer mechanism. Inasmuch as the fluid pressure delivered by the pump is the pressure developed by the impeller increased by the pressure at which fluid is supplied to the pump, such a governing system is subjected to any variations in the pressure at which fluid is supplied to the pump.

It is a more particular object of my invention, therefore, to eliminate the effect on the pressure-responsive element of variations in pressure at which fluid is supplied to the pump.

In accordance with my invention, the relief valve is subjected in closing direction to the pressure of the fluid supplied to the pump. Thus the pressure in the enclosed space is increased by the same amount. Since the variations in the pump supply pressure thus equally affect the fluid pressures on opposite sides of the pressure-responsive element, the effect thereof on said element is eliminated.

The above and other objects are effected by my invention, as will be apparent from the following description and claims taken in connection with the accompanying drawing, forming a part of this application, in which:

The single figure is a diagrammatic view of the governing mechanism, parts thereof being shown in section.

Referring now to the drawings more in detail, I show a valve 10 for controlling the admission of motive fluid to a prime mover. The governing mechanism for controlling the same includes a centrifugal pump 11, having an impeller 12 mounted on the shaft 13 of the prime mover to be governed. Fluid is supplied through a conduit 14 to the inlet chamber 15 of the pump at a positive pressure, by an ejector 16. The latter is motivated by fluid pressure discharged from the pump 11, and entrains fluid flowing by gravity from a reservoir 17.

The fluid pressure developed by the pump 11 controls a fluid pressure relay mechanism indicated generally by the numeral 18, which operates the admission valve 10 in accordance therewith. The relay mechanism includes a casing 19 having a cylinder 21 formed therein. An operating piston 22, connected to the valve 10 by means of a stem 20, is disposed in the cylinder 21 and is biased to close the valve 10 by springs 23.

The relay mechanism further includes a pilot valve 24, disposed in a sleeve 25 fixed in the casing 19. The sleeve 25 has ports 26 and 27, communicating with the upper and lower ends, respectively, of the cylinder 21. It is further provided with inlet ports 28, communicating with a chamber 29 formed in the casing 19 to which fluid under pressure is admitted through an opening 30. It is also provided with discharge ports 31 and 32, communicating with a discharge chamber 33 in the casing from which fluid is discharged through an opening 34.

The pilot valve 24 is formed with piston portions 35 and 36, which cover the ports 26 and 27, respectively, in normal or cut-off position of the pilot valve. The latter is further provided with piston portions 37 and 38 at the upper and lower ends thereof, respectively.

The pilot valve is formed with a hollow interior and a closed upper end. It is connected at its upper end to the upper end of a spring 39 disposed within the interior thereof. The lower end of the spring is connected to the upper end of a stem 41, extending through the casing and connected at its lower end to

a lever 42 intermediate the ends of the latter. The lever 42 is pivotally connected at one end to the stem 20 and at its other end to a stationary fulcrum 43.

- 5 The pilot valve 24 is also the pressure-responsive element of the present construction. Fluid pressure delivered by the pump 11 is conveyed through a conduit 44 to the lower end of the sleeve 25 and biases the pilot valve 24 upwardly in opposition to the force of the spring 39. The upper end of the sleeve opens into a chamber 45 in the casing, into which a restricted flow of fluid is provided, as by an orifice 46 in the closed end of the pilot valve.
- 10 15 The chamber 45 is provided with a discharge opening 47, controlled by a relief valve 48, which is biased to closed position by a spring 49 and which thereby imposes a pressure on the fluid in the chamber 45. The upper end of the spring 49 abuts against a movable spring-holding member 51, controlled by a lever 52, by means of which the spring deflection, and thus the fluid pressure in the chamber 45, may be varied.
- 20 25 The relief valve 48 is disposed in a chamber 53, into which flows the fluid which escapes through the opening 47 from the chamber 45. The chamber 53 communicates with the conduit 14 by means of a conduit 54. The fluid flowing into the chamber 53 is thereby returned to the pump inlet chamber 15, and the pressure of the fluid in said pump inlet chamber and the pump supply conduit 14 is thus maintained in the chamber 53.
- 30 35 The fluid pressure in the chamber 53 is imposed on the relief valve 48, biasing the same in closing direction. The pump inlet pressure is thus imposed on the fluid in the chamber 45, in addition to the pressure imposed by the force of the spring 49 on the relief valve.
- 40 45 The chamber 45 is adapted to communicate with a drain chamber 55 through an opening 56 controlled by a valve 57. The latter is connected to a piston 58 which is subjected to the pump inlet pressure, communicated to the chamber 59 from the chamber 53 through a passage 61. The piston is biased in opposition to the fluid pressure by a spring 62 with such a force that when the pump inlet pressure decreases below a predetermined pressure, the piston moves the valve 57 to uncover the opening 56, and the fluid pressure in the chamber 45 is released.
- 50 55 The operation of the above-described embodiment is as follows:

The pilot valve 24 is biased upwardly by the fluid pressure delivered by the pump 11. This fluid pressure is opposed by the fluid pressure in the chamber 45, and the excess or resultant fluid pressure moves the pilot valve upwardly to deflect the tension spring 39.

60 65 Upon increase in speed of the prime mover, the increased pump pressure effects upward movement of the pilot valve and increased

deflection of the spring 39. As will be apparent from the drawing, the ports 26 and 28 will be placed in communication, as will also the ports 27 and 32. Fluid under pressure from the chamber 29 is thus supplied to the upper end of the cylinder 21, and the fluid in the lower end thereof is discharged to the chamber 33. The piston 22 is moved downwardly to effect decreased opening of the admission valve 10, until the pilot valve is restored to cut-off position by the stem 20 through the link 42, the stem 41 and the spring 39.

70 75 Upon decrease in speed, the fluid pressure is decreased, and the pilot valve 24 is moved downwardly by the spring 39. The relay mechanism then operates in the reverse manner to effect increased opening of the admission valve 10.

80 85 The variations in pressure of the fluid supplied to the pump at its inlet affect the pressure of the fluid delivered by the pump in like manner. For example, if the pressure of the fluid supplied to the inlet chamber by the ejector 16 increases by one pound per square inch, due to change in viscosity or to one of several other causes, the fluid pressure in the lower end of the sleeve 25 is also increased by one pound per square inch. However, the fluid pressure in the chamber 53 is increased by that amount, and hence the pressure in the chamber 45 is likewise increased by one pound per square inch, thus offsetting the increased pressure below the pilot valve. Thus the pilot valve 24 is entirely unaffected by the variations in the pump supply pressure, and the governing action of the governing mechanism as a whole is likewise not affected by such variations.

90 95 The pressure-relief valve 48 and the means for varying the spring force thereon constitute the speed changer mechanism. By increasing the compression of the spring 49, the fluid pressure in the chamber 45 is increased, which means that a higher speed of the shaft 13 is required to provide sufficient fluid pressure beneath the pilot valve 24 to oppose the increased pressure in said chamber, and to bring the same to cut-off position. By decreasing the spring compression, the speed setting is lowered, as will be apparent.

100 105 It is to be noted that the pressure in the chamber 45 is equal to the sum of the fluid pressure in the chamber 53 plus the force of the spring 49 on the valve 48. Thus the fluid pressure in the chamber 53 modifies the action of the speed changer mechanism only to eliminate the effect on the pilot valve of variations in pump inlet pressure, and the operation of the speed changer mechanism in changing the speed setting of the governing mechanism is not affected.

110 115 Should the pump inlet pressure decrease to such an extent as to indicate an abnormal condition of the fluid pressure system, the

valve 57 releases the fluid pressure in the chamber 45, as described above. The resultant or effective fluid pressure biasing the pilot valve 24 upwardly is thus increased by 5 the amount of this pressure, and the upward movement of the pilot valve effects closing of the admission valve 10. This part of the mechanism is not part of the present invention, but is described and claimed in an application of O. N. Bryant and A. F. Schwenderer, Serial No. 350,608, filed March 28, 1929.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically 20 set forth in the appended claims.

What I claim is:

1. In a fluid pressure governing mechanism for a prime mover, the combination of a pump developing fluid pressure varying with the speed of the prime mover, means for supplying fluid at a positive pressure to the inlet of said pump, a pressure-responsive element subjected in one direction to the fluid pressure delivered by said pump, means controlled by the pressure-responsive element for controlling the prime mover, means providing an enclosed space, the pressure-responsive element being subjected in the opposite direction to the fluid pressure therein, means providing a restricted flow of fluid under pressure into said space, a pressure-relief valve controlling the fluid pressure therein, and means for subjecting the pressure-relief valve in closing direction to the fluid pressure at the inlet of the pump, whereby variations in said pump inlet pressure are transmitted to the fluid pressure in the enclosed space to compensate for similar variations in the fluid pressure delivered by the pump.

2. In a fluid pressure governing mechanism for a prime mover, the combination of means providing a fluid pressure varying with the speed of the prime mover, means for supplying fluid under positive pressure to the inlet of said means, a pressure-responsive element subjected in one direction to the fluid pressure delivered by the first-mentioned means, means controlled by the pressure-responsive element for controlling the prime mover, means providing an enclosed space, the pressure-responsive element being subjected in the opposite direction to the fluid pressure therein, means providing and controlling a fluid pressure in said space, and means for modifying the action of the last-mentioned means in response to variations in the fluid pressure at said inlet, whereby said variations are transmitted to the fluid pressure in said enclosed space to 65 compensate for similar variations in the fluid

pressure delivered by the first-mentioned means.

3. In a fluid pressure governing mechanism for a prime mover, the combination of a centrifugal pump developing fluid pressure varying with the speed of the prime mover, means for supplying fluid at a positive pressure to the inlet of the pump, a pressure-responsive element subjected to the fluid pressure delivered by said pump, means controlled by the pressure-responsive element for controlling the prime mover, means for subjecting the pressure-responsive element to a second fluid pressure and for controlling said pressure, and means for modifying the action of the last-mentioned means in response to variations in the pump inlet pressure to compensate for similar variations in the fluid pressure delivered by the pump.

4. In a fluid pressure governing mechanism for a prime mover, the combination of a centrifugal pump developing fluid pressure varying with the speed of the prime mover, means for supplying fluid at a positive pressure to the inlet of the pump, a pressure-responsive element subjected to the fluid pressure delivered by said pump, means controlled by the pressure-responsive element for controlling the prime mover, means for subjecting the pressure-responsive element to a second fluid pressure and for controlling said pressure, means for varying the setting of said pressure control means to vary the speed setting of the governing mechanism, and means for modifying the action of the pressure control means without changing said setting in response to variations in the pump inlet pressure to compensate for similar variations in the fluid pressure delivered by the pump.

5. In a fluid pressure governing mechanism for controlling a prime mover in response to three variable fluid pressures, the combination of means providing a fluid pressure varying with the speed of the prime mover, a pressure-responsive element subjected to said fluid pressure, means controlled by the pressure-responsive element for regulating the admission of motive fluid to the prime mover, means for subjecting the pressure-responsive element to a second fluid pressure, means for controlling the second fluid pressure, means for applying a third fluid pressure to the last-mentioned means for modifying the action thereof, and a spring biasing the pressure responsive element in opposition to the resultant force of the fluid pressures acting thereon.

6. In a fluid pressure regulating mechanism for controlling an operated member in response to three variable fluid pressures, the combination of a pressure-responsive element subjected to a variable fluid pressure, means for subjecting the pressure-responsive element to a second fluid pressure, means for

controlling the second fluid pressure, means for applying a third fluid pressure to the last-named means to modify the action thereof whereby the variations in the third fluid pressure are transmitted to the second fluid pressure and imposed on the pressure-responsive element, and means controlled by the pressure-responsive element for controlling the operated member.

- 10 7. In a fluid pressure regulating mechanism for controlling an operated member in response to three variable fluid pressures, the combination of a pressure-responsive element subjected to a variable fluid pressure, means for subjecting the pressure-responsive element to a second fluid pressure, means for controlling the second fluid pressure, means for varying the setting of said pressure control means to vary the setting of the regulating mechanism, means for imposing a third fluid pressure on the pressure control means to modify the action thereof without changing said setting whereby the variations in the third fluid pressure are transmitted to the second fluid pressure and imposed on the pressure-responsive element, and means controlled by the pressure-responsive element for controlling the operated member.
- 15 8. In a fluid pressure regulating mechanism for controlling an operated member in response to three variable fluid pressures, the combination of a pressure-responsive element subjected to a variable fluid pressure, means providing an enclosed space, means providing a restricted flow of fluid into said space, a pressure-relief valve controlling the escape of fluid from said space and the fluid pressure therein, means for imposing a third fluid pressure upon the pressure-relief valve whereby the fluid pressure in said space is subjected to the variations in the third fluid pressure, said pressure-responsive element being also subjected to the fluid pressure in said space, and means controlled by the pressure-responsive element for controlling the operated member.

In testimony whereof, I have hereunto subscribed my name this 24th day of July, 1929.

HENRY F. SCHMIDT.
